DRYING APPARATUS

Bryce M. Hess, Chicago, Ill.

Application July 17, 1929. Serial No. 378,933

4 Claims. (Cl. 34—34)

My invention relates, more particularly, to the drying of material, as for example, and more especially, grain.

One of my objects is to provide means whereby the temperature in the drying portion of the apparatus become highly excessive and particularly where spontaneous combustion of the material occurs, the flow of drying medium thereto will be automatically discontinued.

Another object is to provide, in a drying apparatus comprising a furnace supplying the drying heat, for utilizing all of the heat produced by the furnace and in the most direct manner to the end that the drying operation may be performed with the minimum amount of fuel and thus with greater economy.

Another object is to provide in a drying apparatus of the character above stated, for the mixture of the hot gases of combustion and the air without requiring the use of metal tubes located in the furnace and subjected to the hot products of combustion and through which the air, out of communication with the interior of the furnace, passes for superheating, or other metallic radiating surface subjected to radiant heat from the furnace, the use of such tubes or radiating surfaces presenting a disadvantage in that they often become burned out or warped and disturb the normal functioning of the apparatus.

Another object is to provide an apparatus in which the temperature in the drying space will be maintained substantially uniform regardless of sharp fluctuations in the temperature of the hot gases supplied to the mixing chamber from the furnace.

Another object is to reduce the heat losses in apparatus of the general character above stated.

Another object is to provide for the maintaining of a substantially uniform temperature in the drying space regardless of the degree of temperature required for the drying operation.

Another object is to provide, in a drying apparatus comprising a furnace supplying the drying heat, for the automatic control of the combustion-supporting air to the furnace responsive to temperature conditions in the drying portion of the apparatus; and other objects as will be manifest from the following description.

Referring to the accompanying drawings:

Figure 1 is a view in vertical sectional elevation of drying apparatus embodying my improvements.

Figure 2 is a similar view of certain details of the apparatus of Fig. 1.

Figure 3 is a similar view of the lower end of

the conduit forming a part of the course through which the products of combustion from a furnace, forming a part of the apparatus, are directed to the drying chamber portion of the apparatus.

Figure 4 is a section taken at the line 4 on Fig. 3 and viewed in the direction of the arrow.

Figure 5 is a broken enlarged plan view taken at the line 5 on Fig. 1 and viewed in the direction of the arrow.

Figure 6 is a view in vertical sectional elevation of one of the similar damper controlling motors forming parts of the apparatus.

Figure 7 is a view somewhat in the nature of a diagram of the mechanism for automatically shutting off the supply of air to the drying chamber in the event of a highly excessive temperature therein; and

Figure 8, a similar view of a modification of the control mechanism shown in Fig. 7.

In the particular apparatus illustrated 9 represents the enclosing walls of a grain drier shown as provided at its upper end with a feed hopper 10 for receiving the material to be dried. Below the hopper 10 are drying racks represented generally at 11 and below the drying racks are cooling racks represented at 12.

These racks may be of any desired construction, as for example as shown in United States Letters Patent No. 1,210,166 granted to George H. Hess, December 26, 1916, and serve to hold the material to be dried and thereafter cooled, and through which the material gravitates to the hopper outlet 13 at the desired speed by any feed-controlling mechanism, as for example as disclosed in said patent.

The drying racks 11 are arranged parallel with each other and in a horizontal series in spaced relation, as shown in Fig. 5, the racks 12 constituting a downward continuation of the racks 11. The spaces between the racks 11 are closed at their upper ends by peaked partitions 14 and also closed adjacent the junctures of the racks 11 and 12 by similar partitions.

As shown in said patent the opposed side walls of the racks 11 and 12 are of openwork form as by constructing them of louvered plates which serve to retain the grain within the confines of the racks while permitting of the passage of air through them.

Alternate ones of the spaces between the racks 11 and 12 at the left-hand ends thereof in Fig. 1 are closed by imperforate end walls, their opposite ends being open, the others of said spaces being closed by imperforate walls at the right-

hand ends thereof in Fig. 1 with their opposite ends open.

The open ends of these spaces at the right-hand ends thereof in Fig. 1 communicate, respectively, with compartments 15 and 16, separated by a partition 17 and in which the racks 11 and 12, respectively, are located, the end walls of these compartments containing openings 18 and 19, respectively, to the atmosphere.

10 It will be understood from the foregoing that air supplied, as hereinafter described, to the open ends of the spaces between the racks 11 and between the racks 12 will pass through the apertured sides of the racks 11 and 12 and the grain interposed therebetween thus exerting on the grain a drying or cooling action, as the case may be.

Located in the compartment 15 at the left-hand side of Fig. 1 is a blower 20 the outlet of which communicates with a series of ducts 21 which communicate, respectively, with those of the spaces between the racks 11 which are open at this end of the structure; and located in the compartment 16, at the left-hand side of Fig. 1, 25 is a suction blower 22 the inlet of which communicates with this end of the compartment 16 and thus with those of the spaces between the racks 12 which are in communication with this portion of the compartment, the outlet of the blower 22 being represented at 23.

In the particular construction shown the source of heated gaseous medium for drying the grain in the racks 11 is a furnace represented at 24 and which may be of any desired construction, the illustrated arrangement utilizing the hot products of combustion from the furnace, as 35 to the gaseous medium referred to.

The furnace shown is of the coal burning type comprising a combustion chamber 25 above a grate 26, with the space 27 below the grate in communication with an air inlet 28 controlled by a hinged door 29 and through which the air for supporting combustion of the fuel is introduced into the furnace.

45 Opening at its lower end into the outlet 30 of the combustion chamber 25 is a pipe 31 provided with a slide damper 32, this pipe, which is open at its upper end as indicated at 33, being surrounded by a pipe 34 concentrically disposed relative to the pipe 31 and spaced therefrom as shown, the pipe 34 containing series of louvered openings as represented at 35 for the admission of air, from the atmosphere, into this pipe, and the pipe 31 communicating with a smoke pipe 36 containing a damper 37.

55 The upper end of the pipe 34, which extends above the upper end of the pipe 33 opens into a pipe 38 between the ends of the latter, the pipe 38 communicating at one end with the atmosphere as represented at 39 and at its opposite end opening into the suction inlet of the blower 20.

The apparatus shown comprises means for automatically regulating the temperature in the 65 drying portion of the apparatus, these means comprising dampers 40 rotatably mounted at shafts 41 in the upper end of the pipe 34, above the upper end 33 of the pipe 31, and a series of dampers 42 rotatably mounted at shafts 43 in the pipe 38 between the point at which the pipe 34 opens into the pipe 38 and the inlet 39 of the latter.

70 The shafts 41 are connected with levers 44 and 45 which are pivotally connected together by a link 46; and the shafts 43 are connected

with levers 47 pivotally connected together by a link 48. One of the shafts 43 is provided with another lever 49 which is connected with the lever 45 by a link 50, the latter being pivotally connected with both of these levers.

80 The arrangement of the dampers 40 and 42, together with the lever connections between them, are such that as the dampers 40 move toward closed position the dampers 42 move toward open position, and vice versa.

85 The simultaneous movement of the dampers 40 and 42 as stated, responsive to temperature variations in the drying portion of the apparatus, is controlled by a motor represented at 51 and comprising a lever 52 fulcrumed between its 90 ends on a stationary support 53 and pivotally connected adjacent one end, as represented at 54, with one end of a link 55 the other end of which is pivotally connected at 56 with an extension 57 of the lever 44.

95 A spring 58 operates, unless restrained, to rock the lever 52 in a direction for closing the dampers 40 and opening the dampers 42.

The lever 52 between its fulcrum 53 and the connection thereof with the spring 58 operatively engages, through a pivoted link 59, the outer end of a rod 60 connected with the free end of a bellows diaphragm 61 the opposite end of which is secured to a wall of a casing 62 containing an opening to receive a pipe 63 which communicates with the fixed end of the diaphragm 61. The pipe 63 opens into a pipe 64 which leads from any suitable source of compressed air, as for example a compressed air tank represented at 65, the pipe 64 being provided between the 100 tank 65 and the point at which it communicates with the pipe 63, with a constriction which may be produced by adjusting the stem 66 of a valve 67.

105 The pipe 64 continues upwardly and opens into 115 a device, represented diagrammatically at 68 and preferably located in one of the racks 11, for releasing the pressure in the pipe 64 at its upper end responsive to the rise in temperature in the 120 drying portion of the apparatus above that desired to be maintained, and proportionately to such excess of temperature.

125 The device 68 may be of any desired construction such, as for example, that commonly used in heat-controlling systems and comprising a valve cooperating with the open end of the air-pipe (the pipe 64) and operatively engaged, and controlled, by a thermostatic element such as a bar which lengthens under increase of heat and 130 opens the valve.

135 In the operation of the apparatus the air pressure from the tank 65 builds up in the diaphragm 61 causing the latter to assume the position shown in Figs. 1 and 6 in which position the dampers 40 are open and the dampers 42 are closed, whereby hot products of combustion from the furnace, mingled with air drawn into the pipe 34 through the openings 35 therein, and diluted substantially to the minimum, are caused, by the action of the blower 20, to be forced 140 through the racks 11 and the grain therein, the spent air exhausting to the atmosphere through the outlet 18. Should the temperature in the racks 11 exceed that desired, and at which the thermostatic device 68 is set to operate, the pipe 145 64 becomes open to the atmosphere resulting in a drop in pressure of the air in the pipe 63 whereupon the diaphragm 61 contracts causing a movement of the dampers 40 and 42 toward closed and open position, respectively, to reduce the heat of 150

the gaseous medium supplied to the drying racks by the blower 20.

It is also desirable that the supply of air to the furnace through the air inlet 28 be automatically varied responsive to the temperature condition in the racks 11. To this end the door 29 is shown as connected with the lever 52 by a cable 69 shown as passing over stationary pulleys 70 and 71, the arrangement shown being such that as the lever 52 swings in a direction to move the dampers 40 toward closed position, the damper 29 swings toward closed position, and when this lever is moved in the opposite direction to cause the dampers 40 to move toward open position, the door 29 is moved toward open position.

The apparatus shown also comprises means whereby should the temperature in the apparatus become greatly excessive as for example in the event that spontaneous combustion of the material occurs, the flow of gaseous medium to the drying racks 11 is arrested, these means, in the particular construction shown, comprising a series of dampers 72 located in the pipe 38 between the dampers 40 and 42 and the blower 20 and mounted on rotatable shafts 73, these shafts being connected with levers 74 pivotally connected with a link 75, which latter is pivotally connected with a link 76 in turn pivotally connected at 77 with one end of a lever 78 fulcrumed between its ends at 79 on a stationary support.

The other end of the lever 78 is connected with a spring 80 which, unless restrained, rocks the lever 78 to a position in which the dampers 72 are closed, as shown by dotted lines in Fig. 2.

Means are provided for normally holding the lever 78 in the position shown, and in opposition to the action of the spring 80 in which position the dampers 72 are open, these means comprising the same mechanism as that shown in Fig. 6, the bellows diaphragm of which opens into a pipe 81 which communicates with the pipe 64 between the tank 65 and the valve 67, and extends upwardly to a header 82 provided with branch pipes 83 of any suitable number each equipped with any suitable form of device represented at 84 and shown as located above certain of the partitions 14, which operates to release the pressure in the pipe 81 in the event of the rise of temperature in the drying portion of the apparatus to the high degree at which it is desired the flow of gaseous medium to the racks 11, be arrested.

By way of example the devices 84 may be of the fusible type commonly employed in automatic sprinkler systems which operate when subjected to excessive temperature to open to the atmosphere the pipes with which they are connected, by the fusing, under excessive heat, of elements which normally maintain the devices in closed condition.

When the pressure in the pipe 81 becomes reduced by the opening of any one of the devices 84, the spring 80 operates to close the dampers 72 thereby closing the pipe 38 to the atmosphere and to the source of heating medium.

It is also desirable that the blower 20 and suction fan 22 be automatically stopped in the event of the occurrence of such excessive heat in the apparatus as to open the air line at any one of the devices 84, the apparatus shown also effecting this operation.

In Fig. 7 I have illustrated, somewhat diagrammatically, an arrangement whereby simultaneous stopping of the blower 20 and suction fan 22 and closing of the dampers 72 are effected. In this arrangement the motor for operating the blower

20 is represented at 85 and the motor for operating the suction fan 22 is represented at 86. The line wires through which current is supplied to the motors are represented at 87 and 88 these wires being connected with the movable double arm 89 of a switch, the stationary contacts of which are represented at 90 and 91 and connect with the terminals of the motor. The motor 86 is arranged in parallel with the motor 85 by wires 92 and 93 connected with the line wires 87 and 88, respectively, the wires 92 and 93 having interposed therein another switch device the stationary contacts of which are represented at 95 and 96 and are connected with the terminals of the motor 86 and the double movable arm of which is represented at 94.

The two switches referred to are provided with portions 97 and 98 of magnetic material and cooperate with springs 99 and 100, respectively, which tend to hold these switches open. Operating with the members 97 and 98 are electromagnets 101 and 102, respectively, which serve to hold the switches closed, against opening under the action of the springs, after the closing of the switches in any desirable way. The current for energizing the electromagnets 101 and 102 is supplied from a transformer 103 the primary of which and represented at 104 is connected with the wires leading from the switch 89 to the motor 85 and the secondary of which 105 represented at 104a connects with the winding of the magnet 101 by wires 105 and 106 and with the winding of the magnet 102 by wires 107 and 108 connected with the wires 105 and 106.

The arrangement shown also comprises a circuit for short circuiting the secondary 104a responsive to the opening of any one of the devices 84 the means shown comprising a switch device represented at 109, the spring fingers 110 and 111 of which are normally separated and are connected with the wires 105 and 106 by wires 112 and 113, respectively.

The lever 78 has pivotally connected therewith a rod 114 slideable in an opening in the contact strip 110 and provided at its upper end with a head 115 so disposed that when the lever 78 swings to a position in which it closes the dampers 72, the contact 110 will be forced into engagement with the contact 111 thereby short circuiting the secondary circuit of the transformer 103, whereupon the magnets 101 and 102 become de-energized and the switches cooperating therewith automatically open, under the action of the springs 99 and 100, thereby breaking the circuits in which the motors 85 and 86 are interposed.

The control of the motors and the dampers 72 may, if desired, be effected in other ways than that shown in Fig. 7 and above described. For example, such control may be effected electrically, as for example as disclosed in Fig. 8. In this arrangement instead of employing pneumatic means as shown in Fig. 7, I employ a solenoid 116 the core of which represented at 117 is connected, through a link 118, with the link 75 connecting together the several dampers 72, the arrangement being such that when the solenoid 116 is energized it lifts the core 117 to the position shown in Fig. 8 causing the dampers 72 to be in open condition, and when the solenoid becomes deenergized the weight of the several parts, augmented, if desired, by any additional means, such as a spring (not shown), automatically moves to a position in which the dampers 72 are closed.

In place of the fusible devices 84 of the preceding figures I employ at the same locations as de-

scribed of the devices 34, fusible-link circuit-bridging devices 119 disposed in series in circuit with the solenoid 116, the latter being shown as supplied with current from the transformer 103, 5 where the source of supply of current is alternating current, and arranged in circuit with the electromagnets 101 and 102. Where the source of current-supply is direct current, any suitable resistance element is substituted for the transformer 103 to reduce the voltage to the degree desired.

It will be understood from the foregoing that should the temperature at any one of the devices 119 be sufficient to fuse the fusible element thereof, the secondary circuit and in which the magnets 101 and 102 and the solenoid 116 are interposed will become broken whereupon the motor switches will automatically open causing the motors to stop and the dampers 72 will automatically move to closed position.

It will be noted that the arrangement of the valves above referred to controlling the inlet of the products of combustion, whether diluted or not, and the air, at atmospheric temperature, 25 through the inlet 39, into the mixing chamber, operate, under the control of the temperature controlled means, to maintain approximately the same volume and pressure of the mixture of the air and hot gases in the mixing chamber at all 30 times which makes for substantially uniform temperature regulation.

While I have illustrated and described certain embodiments of my invention, I do not wish to be understood as intending to limit it thereto as the 35 same may be variously modified and altered without departing from the spirit of my invention.

What I claim as new, and desire to secure by Letters Patent, is:

1. In drying apparatus, the combination of a 40 member presenting a space to receive material to be dried, a drying gas mixing chamber having an opening directly to the atmosphere, a furnace, a conduit to conduct products of combustion from the furnace to said chamber, a jacket for said conduit having an opening to the atmosphere and arranged to conduct air along the outer surface of said conduit and into said chamber, said conduit and jacket having a common opening into 45 said chamber, a hot gas damper controlling said common opening, a cool air damper controlling said first named opening, means to conduct gases from said chamber to the space in said member, and thermostatic means influenced by heat condition in said space connected to simultaneously and oppositely move said dampers.

2. In a drying apparatus, the combination of a 50 member presenting a space to receive material to be dried, a drying gas mixing chamber having an opening directly to the atmosphere, an air 55

damper for said opening a furnace, a draft damper therefor, a conduit to conduct hot products of combustion from said furnace and opening into said chamber, a hot gas damper for said last named conduit, common actuating means for all of said dampers connected to simultaneously move said draft and hot gas dampers in an opposite direction between open and closed positions from the similar movement of the air damper, and thermostatic means influenced by heat condition in said space for controlling said actuating means, whereby to preserve substantially constant the volume of flow of drying gas to said space and to regulate the temperature in said space.

3. In a drying apparatus, the combination of a member presenting a space to receive material to be dried, a drying gas mixing chamber having an opening directly to the atmosphere, a furnace, means to conduct products of combustion from said furnace having an opening into said chamber, separate dampers for each of said openings, actuating means so connected to each of said dampers as to oppositely move the same toward opening and closing respectively, thermostatically controlled means responsive to heat change in said space to move said actuating means whereby to preserve the volume of flow of drying gas to said space substantially constant while regulating the temperature thereof, a conduit to conduct drying gas from said chamber to said space, a damper in said conduit, and means responsive to a degree of heat in said space above a predetermined temperature to cause complete closure of said last named damper.

4. In a drying apparatus, the combination of a member presenting a space to receive material to be dried, a drying gas mixing chamber having an opening directly to the atmosphere, a furnace, means to conduct products of combustion from said furnace having an opening into said chamber, separate dampers for each of said openings, actuating means so connected to each of said dampers as to oppositely move the same toward opening and closing respectively, thermostatically controlled means responsive to heat change in said space to move said actuating means whereby to preserve the volume of flow of drying gas to said space substantially constant while regulating the temperature thereof, a conduit to conduct drying gas from said chamber to said space, a damper in said conduit, a fan in the line of said conduit to provide a force feed of said drying gas, means in said space responsive to a degree of heat in excess of a predetermined temperature to cause complete closure of said last named damper, and means set into action by said excess heat responsive means to cause stoppage of said fan.

BRYCE M. HESS.
